ATTY'ST.

UNITED STATES PATENT OFFICE.

PERCY BENJAMIN BARNARD, OF OTTAWA, ONTARIO, CANADA.

SHADE-ROLLER BRACKET.

1,372,390.

Specification of Letters Patent. Patented Mar. 22, 1921.

Application filed March 29, 1920. Serial No. 369,719.

To all whom it may concern:

Be it known that I, PERCY BENJAMIN BARNARD, a subject of the King of Great Britain, a resident of the city of Ottawa, Province of Ontario, Dominion of Canada, have invented certain new and useful Improvements in Shade-Roller Brackets, of which the following is a specification.

This invention relates to improvements in shade roller brackets, and the objects of the invention are to facilitate mounting a shade on a window or if necessary, a double shade, in which latter case, the shades are operated in opposite directions and overlap each other, thereby excluding all light in the space between the rollers of the different shades, to simplify the form of the bracket and keep both shades as near as possible to the window, and generally to adapt it to better perform the functions required of it.

With the above and other objects in view, the invention consists essentially of the improved construction particularly described and set forth in the following specification and accompanying drawings forming part of the same.

In the drawings:

Figure 1 is a perspective view of a window frame showing the improved bracket mounted thereon, having double shades which are operable in opposite directions, and with the space between the rollers of the shades covered.

Fig. 2 is a side elevation of the same.

Fig. 3 is a side elevation of one of my brackets attached to the inner face of a window frame.

Fig. 4 is an enlarged side elevation of the bracket shown in Fig. 3.

Fig. 5 is a fragmentary perspective view of a portion of the window frame showing a single roller bracket in position thereon.

Fig. 6 is an enlarged side elevation of the single bracket shown in Fig. 5.

Fig. 7 is a front elevation of the locking pulley used on the window frame.

Like characters of reference refer to like parts in the several figures.

Referring to the drawings; A represents a window frame of any usual construction on which a double roller shade is to be mounted.

To facilitate positioning this double roller

shade, I provide a bracket 10 which may be secured to the frame of the window by screws or the like, which bracket consists of a flat plate having a flange 11 at right angles thereto, through which screws or the like pass to secure the bracket in position.

Another bracket 9 is used having orifices 8 in which are journaled the pintles of the shade roller.

The plate 10 is provided at the upper end with an angularly-disposed opening or slot 12 having a constricted opening 13, the wall 65 of the opening diverging and terminating in a vertically disposed wall 14 and horizontally disposed wall 15.

Adjacent to the lower end of the plate 10, a horizontally-disposed slot 16 is provided 70 with a pin 17 bridging the front of the slot 16 for an object which will be made clear hereafter.

A bracket 9 is used with one of my improved brackets 10, the bracket 9 receiving 75 and journaling the pintles of the shade rollers, and the bracket 10 accommodates the spring projections of the rollers.

The roller 18 has its spring controlled projection engaging with the upper slot 12, 80 while the lower roller 19 has its spring controlled projection engaging with the horizontally-disposed slot 16 and the pin 17 prevents the lower roller becoming displaced.

When the lower roller 19 is in engagement 85 with the horizontally-disposed slot 16, then the dogs which are common to such rollers hang in a neutral position and will not engage the spring controlled projection and render the same inoperative, so that it will 90 be clear that the shade 20 mounted on the lower roller will always be in tension, and will not belly or flap when being lowered. It will be seen that the horizontal position of the slot 16 causes the slot to be at substantial right angles to the plane of the shade 23, in which position the dogs on the shade roller will hang in neutral position, leaving the roller free to turn without engagement of the dogs in the spring controlled projection.

The shade 20 on the lower roller 19 extends upwardly, and a flexible member 21 is attached to the same and passes over a guide and stop pulley 22, which is shown 105 in detail in Fig. 7, and the flexible member

will, when pulled sidewise, lock on the pulley 22 and thus hold the shade 20 in the desired position.

The shade 23 of the roller 18 extends 5 downwardly behind the roller 19 and the dogs of the roller 18 function in the ordinary manner as with an ordinary shade.

It is not thought necessary to describe the rollers as they do not form part of the present invention, but are only utilized with the 10 particular form of bracket, which forms the subject matter of the present invention.

In some cases a single shade only is used, which is operated upwardly from the 15 bottom of the window, and in this case a single bracket 24 is secured to the frame of the window.

This bracket is provided with a horizontally-disposed slot 25 to receive the spring 20 projection of the roller.

In this position, the dogs on the roller will be held in neutral position, and the shade carried by the roller will therefore at all times be in tension.

25 When the double form of bracket is used, the shade rollers are mounted thereon as illustrated in Figs. 1 and 2, then the space between the rollers is closed by a double shade namely 23, and 20, so that light cannot 30 enter through this space.

The shade 20 will be actuated by a flexible member 21 and as the dogs of the roller 19 are in a neutral position, then the shade is always tensioned during a winding or lowering 35 operation.

During the lowering operation, the shade cannot belly or sag but will be rolled on its roller 19.

When a single shade is used it would be 40 operated upwardly and then the dogs on the roller will be in neutral position and the

shade on the roller will be in tension, and when the shade is being lowered it will wind around from the roller and will not sag.

In using shades of this description, it will 45 be clear that in ventilating a room by opening the top of the window, the shade 20 may be lowered so that it will not flap about with the wind; it will not extend above the open portion; the same thing applies to shades 50 used in the manner shown in Fig. 5.

From the above description it will be seen that I have invented a window roller bracket which can be advantageously utilized in mounting shades on a window, and which 55 permits of double shades being used without any light entering between the rollers.

The shade rollers and stop pulley have not been described in detail because they do not form part of the present invention, and the 60 brackets 10 only constitute the present invention.

As many changes could be made in the above construction and many widely different embodiments of my invention within 65 the scope of the claim, constructed without departing from the spirit or scope thereof, it is intended that all matter contained in the accompanying specification and drawings shall be interpreted as illustrative and 70 not in a limiting sense.

What I claim as my invention is:

A shade roller bracket, having a slot therein extending substantially at right angles to the plane of the shade, whereby when the 75 end of the shade roller is engaged with the brackets, the dogs on the shade roller will remain in neutral position.

In witness whereof I have hereunto set my hand.

PERCY BENJAMIN BARNARD.
